UNITED STATES PATENT OFFICE.

JOHN ALBIN ANDERSON, OF LOCKPORT, ILLINOIS.

COMBINED BUSHING AND VALVE.

1,340,810.

Specification of Letters Patent. Patented May 18, 1920.

Application filed July 10, 1918. Serial No. 244,260.

To all whom it may concern:

Be it known that I, JOHN ALBIN ANDERSON, a citizen of the United States of America, residing at Lockport, in the county of Will and State of Illinois, have invented new and useful Improvements in Combined Bushings and Valves, of which the following is a specification.

This invention is designed principally to provide a bushing in the form of a conventional pipe bushing in which there is seated a valve, the latter having means for retaining it on its seat, except when a smaller pipe is attached in the bushing whereon the valve is unseated, thereby placing in communication the two parts for which the bushing acts as a connecting means.

Other and further provisions of the invention are made to appear in the following detailed description of the same.

While illustrated and described in a specific embodiment, the invention is not to be restricted to such. Continued use in practice may suggest certain desirable changes or alterations and the right is claimed to make any which do not deviate from the scope of the subjoined claims.

In the accompanying drawings:

Figure 1 is a perspective view showing the practical application of the invention.

Fig. 2 is a longitudinal view through the invention.

Fig. 3 is a transverse sectional view on the line 2—2 of Fig. 2.

As illustrated the invention which is in the form of a bushing is shown as attached to an oil barrel 1 in the head 2 thereof; so that a pipe or cock may be readily attached to the barrel to draw off the latter's contents.

The improved bushing comprises a body 3 with the hexagonal shouldered end 4 by means of which it may be turned with a wrench. This body 3 is threaded internally and externally, the external threads engaging threads in the head 2 of the barrel 1 while the internal threads of the body are intended to receive the external threads of a pipe or cock, not shown. So far as the body itself is concerned, the bushing simulates the conventional pipe bushing or reducing nipple.

At that end opposite the shouldered portion 4, the body is formed with a valve seat 6, so that the valve 7 may seat thereon, the valve itself being of the disk type and provided with a stem 8. Disposed transversely

across the body of the bushing and adjacent to the valve seat 6 there is a transverse member or web 9 which is relatively narrow so that it may not obstruct the body at the valve end of the latter. This web 9 has formed therein a hole centrally positioned both with respect to the length and width of the web and the valve stem 8 passes loosely through this hole, in order that longitudinal movement imparted to the stem may serve to seat or unseat the valve, depending on the direction in which the stem is moved.

The stem 8 extends through the body toward the shouldered end of the latter and near its free end is formed with a transverse member or guide 10, the latter being of sufficient length to permit its ends to slidably engage in longitudinal recesses 11 cut in the interior wall of the body and at diametrically opposite sides of the latter. This guide or transverse member 10 serves to preclude any angular movement of the valve but its sliding engagement with the recesses 11 permits longitudinal movement of the stem to seat or unseat the valve.

In order that the valve may be held normally seated, a spiral spring 12 is compressed between the web 9 and the guide 10 and is positioned so as to be in surrounding relation to the stem 8.

It is obvious from the construction disclosed that the attachment of the body to the head of the barrel 1 will serve as a means for attachment of a pipe or cock to the barrel but this means will be closed, if the valve 7 is allowed to seat and it will be allowed to seat as long as no pressure is exerted on the guide 10 on that face opposite that against which the spring 12 presses. When a pipe or cock is screwed into the body 3, its end will bear on the guide 10 and continued screwing of the said pipe into the body will thus operate to unseat the valve.

As a result of the pressure exerted upon the guide 10 the unseating of the valve 7 serves to then place the pipe into communication with the interior of the barrel and will permit the flow of a liquid from the barrel into the pipe.

The stem 8 is provided with a threaded extension 5 just above the guide 10 and on this extension there is received a disk 13 having a square hexagonal boss 14 by means of which the disk may be turned to seat the disk on the shouldered end of the

body to lock the valve 7 in a position of closure, as is apparent.

It is obvious that the improved device may be used as a bushing for beer kegs as a means for permitting the ready attachment of spigots; that it may be used as a closure for one pipe for which an extension is attached; and that it is useful in various other instances for performing the character of service set forth.

The invention having been described what is claimed as new and useful is:

1. A device of the kind described comprising a hollow cylindrical body threaded both exteriorly and interiorly, the interior wall having longitudinal recesses formed at diametrically opposite points, the body having a valve seat formed at one end and carrying a web positioned transversely thereacross and adjacent to the valve seat, a valve, a valve stem connected with the valve and passing slidably through the web, a guide carried on the stem at the end remote from the valve, the guide having its ends in sliding engagement with the said recesses, a spring in surrounding relation to the stem and compressed between the guide and the web, the stem being provided with a thread-

ed extension at the end remote from the valve, and a disk engaged on said threaded end for axial movement along the stem to engage the cylindrical body on the end and lock the valve in closed position when not in use.

2. A device of the kind described comprising a hollow cylindrical body threaded both exteriorly and interiorly, the interior hollow having longitudinal recesses formed at diametrically opposite points, the body having a valve seat formed at one end and carrying a web positioned transversely thereacross and adjacent to the valve seat, a valve, a valve stem connected with the valve and passing slidably through the web, a guide carried on the stem at the end remote from the valve, the guide having its ends in sliding engagement with the said recesses, and a spring in surrounding relation to the stem and compressed between the guide and the web, whereby an exteriorly threaded member screwed into the body may bear upon the guide to unseat the valve for the purpose specified.

In testimony whereof I affix my signature.

JOHN ALBIN ANDERSON.
